Assistant Examiner — Samina Vieth

(57) **CLAIM**

The ornamental design for a protective case for tablet computer, as shown and described.

DESCRIPTION

FIG. 1 is a perspective view of a protective case for tablet computer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the protective case for tablet computer in an open state.

The broken lines in the drawings are for the purpose of illustrating portions of the protective case for tablet computer that form no part of the claimed design.

1 Claim, 9 Drawing Sheets
